Crown Rheostat & Supply Co., Chicago, Ill., a
corporation of Illinois

Application November 6, 1944, Serial No. 562,100

9 Claims. (Cl. 51—164.5)

1

The present invention relates to grinding and finishing materials adapted to be used in tumbling grinding or tumbling finishing. It is the purpose of this invention to provide a mass of particles of controlled size and contour which is applicable in connection with such abrasives as pumice, emery, tripoli and ground oyster shells and the like in tumbling machines for the purpose of abrading and grinding the surfaces of metal parts.

In the grinding or abrading of the surfaces of metal parts by the tumbling operation, it is desirable to decrease rotation resistance in the mass that is within the interior of the tumbler. It is a fact that most of the movements of the parts against each other for grinding purposes takes place along a diagonal surface area that is continually changing as the tumbling barrel rotates. We find that by making the particles, which form the support for the metal parts to be finished, of regular shape so that their major surfaces are smooth, we get the best grinding action. We likewise avoid scratching or spoiling the surface by virtue of sharp points cutting into a relatively smooth surface.

We are aware that it has been proposed to utilize irregular surfaced random shape stones for this purpose. Likewise it is well known in the art to utilize spherical members such as balls of material for the purpose of tumbling. Our invention distinguishes from such a device by providing a material composed of particles of controlled size and contour, such particles having relatively few angles, but usually having at least two substantially parallel faces connected by other surfaces to define a particle which is regular in shape.

Other more detailed advantages of our invention, will appear more fully from the following description, reference being made to the accompanying drawings wherein a preferred form of the invention is shown. It must be understood, however, that the drawings and description are illustrative only, and are not to be taken as limiting the invention, except insofar as it is limited by the claims.

In the drawings:

Figure 1 is a cross sectional view through a tumbling barrel illustrating the manner in which the product embodying our invention is employed with articles to be finished;

Figure 2 is a perspective view of an article to be finished showing the way in which the regular shaped particles engage the article to remove flashing or burrs therefrom;

2

Figure 3 is a perspective view of one specific shape of tumbling particle;

Figure 4 is a perspective view of another shape of tumbling particle;

Figure 5 is a perspective view of a further shape of tumbling particle embodying our invention; and

Figure 6 is a perspective view of still another form of tumbling particle embodying certain characteristics of our invention.

Referring now to the drawings, Figure 1 illustrates somewhat diagrammatically the nature of the tumbling barrels wherein the materials embodying our invention are employed. A tumbling barrel of this character usually comprises a shell 10 of metal with a lining 11 of some other wear resistant material such as wood. The lining 11 is removable so that it can be replaced as it wears out. The tumbling barrel is normally filled with a mass of metal articles 12 which are to be ground or polished, an abrasive material 13 such for example, as pumice, emery, tripoli, etc., a sufficient amount of water, and a mass of particles 14 of controlled size and contour. The abrasive material such as pumice, is of course, in finely divided form. The particles 14, however, are of appreciable size. It has heretofore been proposed to utilize stone such as granite as a supporting mass of particles in which the articles to be finished are carried. According to our invention, we are able to speed up and improve the grinding and finishing of metal articles by utilizing a mass of particles for carrying the metal articles and rubbing the abrasive against them, such particles being of a novel nature so as to gain the greatest advantage from the tumbling action.

The particles 14 in accordance with our invention are made of porcelain or an equivalent vitreous composition. The particles are made regular in shape so that their major surfaces are smooth. Where the major surfaces join, there is an angle, but points as such are avoided in the construction of the particle. We find that we can make the particles with at least two opposed faces substantially parallel and provide the desired amount of angularity. By using these particles we obtain a decreased rotation resistance in the interior of the tumbling barrel which permits rolling of the articles to be finished and accelerates the grinding action of the particles and the associated finely divided abrasive material.

The particle 14 shown in Figure 3 is one which has been found quite effective. This particle is shown in action in Figure 2 upon the surface of the article 12. It will be observed that the par-

title has two end portions 15 and 16 which are substantially parallel to each other. Smooth surfaces 17 at opposite sides of the particle 14, including the curved surfaces 18, are particularly useful in rubbing the abrasive upon the smooth parts of the article 12. There are, however, angular edges such as 19, 20, 21 and 22 on the particle 14. These edges are of such a nature that they will engage projecting flashes 12a and any burrs along the edges 12b of the article 12 to quickly abrade away the flashes and burrs.

In Figure 4 of the drawings, another particle 23 is shown and this particle like the particle 14 has its opposite ends substantially parallel, but between the opposite ends 24 and 25 the particle 23 is substantially triangular in cross sections with the peaks being rounded. This provides three flat surfaces such as the surface 26 arranged at 60 degrees to each other with rounded portions 27 between them. The particle 23 is of regular shape which provides a number of edges 28 at each end for engagement with the surface of the article to be finished.

In Figure 5 of the drawings, the particle 29 whose cross section is a parallelogram with rounded corners is shown. In this form of the invention as in the form shown in Figures 3 and 4, the opposite ends 30 and 31 of the particle are substantially parallel to each other, likewise the smooth flat side faces 32 of the particle are joined to each other by rounded portions 33.

Figure 6 of the drawings illustrates another particle 34 which is distinguished from the other particles by the fact that the only flat surfaces thereto are the two substantially parallel surfaces 35 and 36. The form of device shown in Figure 6 is a disc of porcelain. It has the advantage that it presents long annular opposed edges 37 and 38. However, this form of device is not so satisfactory from the standpoint of rapidly abrading the material as the other forms.

It is within the scope of this invention to utilize any of the regular shaped particles either singly or mixed with each other and with particles of equivalent characteristics. The sizes of the particles may be varied to suit the product which is to be abraded. For large heavier articles it would be necessary to use somewhat larger particles. In some cases a mixture of sizes of particles gives the best results. In all cases, however, we find it advantageous to use particles of a controlled size and contour. The particles must be regular in shape and preferably they should have at least two opposed faces parallel to each other or substantially so.

One advantage obtained by using particles hereinbefore described in a tumbling barrel is the decrease in the difficulty encountered because of particles lodging in holes, slots or recesses in the work. With our material, particle size can be chosen with respect to the work so as to avoid any danger that the particles will plug or stick in recesses, etc. in the work. The regular particles seem to accelerate grinding action on metal parts. This appears in part to be due to the fact that the mingling and rolling or sliding action extends deeper in the mass than it does with stones of irregular shape and random size. When one of the particles slides across the surface or corner of the metal part being ground, a long continuous abrading or cutting stroke usually results because of the fact that a regular shape article has relatively large continuous surfaces which join along an unbroken line. The regular shape and controlled size of the particles is of an advantage also

in screening and separating of the particles from the metal parts being finished. The particles slide easily because they are regular in shape. They do not scratch the work because they are free of sharp points.

From the foregoing description, it is believed that the nature and advantages of our invention will be clear to those skilled in this art.

Having thus described our invention, we claim:

1. An aggregate for use in the process of tumbling articles to grind or finish the surface thereof, the aggregate comprising a mass of porcelain particles each having smooth surfaces some of which are flat and intersect each other at right angles to provide sharp edges, the particles also having rounded surfaces and being free of sharp points and regular in shape.
2. An aggregate for use in the process of tumbling articles to grind or finish the surface thereof, the aggregate comprising a mass of smooth faced particles of vitreous, ceramic material, each of regular shape with at least two faces parallel to each other.
3. An aggregate for use in the process of tumbling articles to grind or finish the surface thereof, the aggregate comprising a mass of porcelain particles, each having smooth surfaces some of which intersect each other to provide relatively sharp edges, the particles being regular in shape.
4. An aggregate for use in the process of tumbling articles to grind or finish the surface thereof, the aggregate comprising a mass of particles of vitreous ceramic material each of regular shape having curved and flat faces with at least two flat faces parallel to each other and said flat faces intersecting curved faces, the meeting of adjacent surfaces of the particle with said parallel faces being at right angles to form sharp edges.
5. An aggregate for use in the process of tumbling articles to grind or finish the surface thereof, the aggregate comprising a mass of particles of vitreous ceramic material of regular shape, said particles each having large flat faces substantially parallel to each other with narrow curved surfaces interposed therebetween and having sharp edges but no sharp points.
6. An abrading particle for use in tumbling apparatus as a means of supporting articles to be finished and rubbing finishing or grinding matter, such as pumice and tripoli, against the articles, said particle comprising an elongated block of vitreous ceramic material of regular shape, said block having substantially parallel end faces, and at least two flat side faces extending from end to end thereof, said end and side faces meeting to provide sharp edges, and said flat side faces having curved faces alternating therewith and smoothly merging therewith.
7. An abrading particle for use in tumbling apparatus as a means of supporting articles to be finished and rubbing finishing or grinding matter, such as pumice and tripoli, against the articles, said particle comprising an elongated block of vitreous ceramic material of regular shape, said block having substantially parallel end faces, and at least three wide flat side faces extending from end to end thereof, said end and side faces meeting to provide sharp edges, and said flat side faces having curved faces alternating therewith and smoothly merging therewith.
8. An abrading particle for use in tumbling apparatus as a means of supporting articles to be finished and rubbing finishing or grinding matter, such as pumice and tripoli, against the articles, said particle comprising a block of vitreous ce-

ramic material of regular shape, said block having substantially parallel end faces, and at least two flat side faces extending from end to end thereof and meeting said end faces in a sharp edge, the flat side faces being separated by smooth rounded surfaces, said smooth rounded surfaces meeting said end faces in sharp curved edges.

9. An abrading particle for use in tumbling apparatus as a means for supporting articles to be finished and rubbing finishing or grinding material, such as pumice and tripoli, against the articles, said particle comprising a block of vitreous ceramic material of regular shape with alternating flat and curved surfaces and flat surfaces perpendicular to both said flat and curved surfaces, said surfaces meeting to provide curved and straight sharp edges, smooth rounded surfaces and no sharp points.
